ATTORNEYS.

UNITED STATES PATENT OFFICE.

DAVID BROOKS, OF VERONA, NEW JERSEY.

CUTTING-MACHINE.

SPECIFICATION forming part of Letters Patent No. 601,868, dated April 5, 1898.

Application filed March 22, 1897. Serial No. 628,649. (No model.)

To all whom it may concern:

Be it known that I, DAVID BROOKS, a citizen of the United States, residing at Verona, in the county of Essex and State of New Jersey, have invented certain new and useful Improvements in Cutting-Machines for Tampico, Leather, &c.; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

15 The objects of this invention are to facilitate and render more easy the operation of cutting tampico, hair, leather, and other fibrous or other material, and especially for service in cutting fibers for brushes, brooms, and the like, to secure a more perfect and uniform cutting, to perform the cutting operation at a reduced expense of labor, and to secure other advantages and results, some of which may be referred to hereinafter in connection 25 with the description of the working parts.

The invention consists in the improved cutting-machine and in the arrangements and combinations of parts thereof, all substantially as will be hereinafter set forth, and 30 finally embraced in the clauses of the claim.

Referring to the accompanying drawings, in which like letters of reference indicate corresponding parts in each of the views, Figure 1 is a front elevation of the improved cutting-machine; and Fig. 2 is a vertical section of the same, taken on line *x*.

In said drawings, *a* indicates a suitable bench or table, at the top of which is formed a narrow casing or inclosure *b* to protect certain operating parts. At the back, below the top board, is a support *c*, suitably secured to the framework of the bench. Said support is preferably of wood and extends above the top of the top board or bench and forms a portion of the box or inclosure *b*, above referred to. To the said bench, at any suitable point therein, is fulcrumed, as at *d*, a pedal or foot-lever *e*, to which is pivoted, at a point between the fulcrum and free end, a connecting-rod *f*, which extends upward into pivotal engagement with a lever *g*, fulcrumed beneath the top board on the bearing *h*. The

said lever *g* has at its end opposite its fulcrum bearing a pivotal connection with a cutting-blade *i*, which latter extends upward 55 from said lever through an opening in the top of the bench and engages a second longer lever *j*, having its fulcrum within the box or case *b* at the back, as at *k*.

By having the lever *j* longer than the lower 60 lever *g* the cutter is, as it is drawn down by the pedal *e* and connections, given a to-and-fro movement, as well as an up-and-down movement, and passes out through a slot in the casing or box *b* into engagement with the 65 bunches of fiber or other matter to be cut, engaging the same with a shearing action by which the cutting is rendered easy and effective.

Upon the top of the bench or table I provide upwardly-extending cutter-blocks *l l*, having an opening between, as at *m*, Fig. 1, into which the cutting-blade enters when it has about terminated its downward-and-forward cutting movement. Said cutter-blocks 70 form one side of a trough or receptacle open at the top, into which the bundles of fiber or other material to be cut can be freely laid from above, the cutting-blade forming the other side of said trough or receptacle. To 75 secure a return movement of the cutter-blade automatically, I have provided a strong spring *n*, secured at the back of the bench, as at *n'*, and consisting of a resilient piece of wood or metal. At the top or free end of said spring 80 it is pivotally joined to a connecting-rod *o*, which extends forward from said spring, through a slot in the box, into pivotal relation to the lever *j*, so as to draw the said lever 85 *j* and knife connected therewith backward 90 when the foot is removed from the pedal.

The lever *g*, beneath the top board of the machine, may be suitably incased and is provided with a guide or guides *p*, adapted to prevent the said lever *g* from moving laterally from its proper vertical relation to the co-operating parts.

In operating the machine the person in charge simply takes a bunch of fibers or other material and inserts it between the 100 cutter-blocks *b* and the forward edges of the cutting-blade *i*. The foot is then placed upon the pedal *e* and is pressed downward, producing a forward-and-downward movement

of the cutter-blade and effects the shearing action by which the bunch of fibers are cut with smoothness.

Having thus described the invention, what 5 I claim as new is—

1. The improved cutting-machine herein described, comprising a bench or table having cutting-blocks affixed to the upper surface thereof and projecting upward, a cutting-blade working in an open slot in the top 10 of said table, and having an up-and-down movement and a movement to and from said blocks, said cutting-blade when in normal position forming with the blocks, the sides 15 of a trough-like aperture into which the bunch of fibers to be cut can be dropped from above, and long and short levers at the op-

posite ends of said cutting-blade and means for operating said levers, substantially as set forth. 20

2. The combination with the bench or table, of the pedal *e*, connecting-rod *f*, long and short levers, *j*, *g*, a cutting-blade connecting said levers, cutter-blocks *l*, *l*, a spring and a connecting-rod *o*, attached to one of the said 25 levers and the spring, all arranged and combined, substantially as set forth.

In testimony that I claim the foregoing I have hereunto set my hand this 8th day of December, 1896.

DAVID BROOKS.
